UNITED STATES PATENT OFFICE.

HUGH IORWERTH ROBERTS, OF LIVERPOOL, ENGLAND.

BALING AND OTHER PRESS.

No. 906,660.

Specification of Letters Patent.

Patented Dec. 15, 1908.

Application filed October 2, 1907. Serial No. 395,589.

To all whom it may concern:

Be it known that I, HUGH IORWERTH ROBERTS, a subject of the King of Great Britain and Ireland, and resident of Liverpool, in the county of Lancaster, England, engineer, have invented certain new and useful Improvements in Baling and other Presses, of which the following is a specification.

10 This invention relates to improvements in presses for pressing and baling cotton, wool, hay, grass, and kindred materials though it may also be used for pressing seeds to remove oil therefrom or for other materials requiring to be pressed, the object being to provide detail improvements upon the class of press described in my British Patent No. 9874 of the year 1903, to render the press more useful and to render it automatic in 20 some of its parts.

The class of press referred to in the aforementioned patent consists generally of an arrangement of toggle levers supported by the press bed and also connected with the 25 movable pressing plate or follower, the levers being operated by a rope or chain connected to a winch so that the follower is lifted up in the direction of the press head. The material to be pressed is first of all 30 placed in a box pivoted to one of the press pillars so that it may be swung into position between the follower and the press head. A duplicate arrangement of boxes is employed so that while one box is in position in the 35 press a second box is being filled with material, the latter being exchanged in position for the former in the press. The material is pressed through the box into a receiving box or chamber also pivoted to one or more of 40 the press pillars and while in this latter box the pressed material may be lashed in bale form after the doors are opened. The press boxes and also the upper press chambers are provided with hinged sides and ends retained 45 together during pressing by suitable catches which are capable of release so that the press boxes may be unhinged and turned away from the body of the press prior to the follower descending while in the case of the 50 press chamber the sides may be unhinged or separated before the bale has been lashed.

My improvements in the class of press just described consists in dividing the press boxes into a plurality of boxes which at the commencement of pressing each form one long box but each section of which is automatically

swung away from the press as the follower enters the second and third box; means connected with each section which can be operated by the movement of the follower to effect 60 the action just described; means for guiding the follower and an improved arrangement of rocking levers and rods connecting them with the toggle levers to enable the latter to be provided with longer bearing hinges or 65 pivots at the point of connection with the follower, this improved arrangement also admitting of the press pillars being brought closer together. The whole of these combined arrangements enable a press to be constructed to deal with either very small or 70 large bales and particularly the former.

My invention will be fully described with reference to the accompanying drawings in which—

75 Figure 1 is a front elevation, partly in section, of a press embodying my improvements, Fig. 2 side elevation of same, Fig. 3 partial plan, Fig. 4 partial front elevation of some of the parts of the press on an enlarged scale 80 and Fig. 5 partial plan to an enlarged scale.

With reference to these drawings I would say that the right hand ends of the toggle levers are broken away owing to exigencies of space but these are exactly similar to the arrangement of levers shown at the left hand side of the first three figures.

a are beams comprising the head of the press supported from cross beams b fixed to the press columns c similar cross beams b¹ 90 being attached to the lower ends of the press columns and passing under beams d located on a basement floor of a building or in a pit. The base beams may be composed of long and short beams longitudinally of the eleva- 95 tion shown in Fig. 1.

e is the press follower to the lower end of which is attached by pins e¹ the upper ends of two similarly-constructed levers f. On the latter between the forks of said levers are 100 mounted chain or rope wheels g supported by shafts f¹, the ends of the shafts carrying wheels i capable of moving on the beams d or on rails secured to them. The shafts f¹ have also coupled to them the outer ends of 105 links or rods h, such links being located outside the range of the press columns instead of between such columns as in the hereinbefore mentioned patent, the other and inner ends of the links being coupled by pins h¹ to 110 the ends of rocking levers j, one on either side of the press and also outside the press

columns. The rocking levers *j* are mounted loosely on a shaft *j*¹ supported in a bearing block *k* fixed to the beams *d* and are designed to act as counter-balance weights. The block *k* is arranged to support the lower ends of pivoted toggle levers *l*, the outer ends of which are coupled to the levers *f* by pins *l*² fixed at or about the center between the pins *e*¹ and shafts *f*¹.

- 10   *m* is a chain, rope or the like which passes round the wheels or pulleys *g*, one end being attached to the bed *k* while the other end is passed round a guide pulley *f*² carried by the beams *d* and thence taken upwards and attached to the winding barrel of a winch or the like that may be operated either by hand or power.

With the exception of the arrangement of the coupling rods *h* and counter-balance levers *j* and the attachment of the rope to bed *k* the general arrangement of levers is virtually the same as in my former patent. The placing of the rocking levers *j* and rods *h* outside the press columns *c* however, enables the points of connection of the levers *f* with the pins or shafts *e*¹ to be wider in a transverse direction thereby providing a much wider bearing in each case for supporting the press follower and also allows the columns to come closer together thus reducing the strain on the head and bed and making the press more compact.

n indicates generally the press boxes but instead of employing a single box on each of two of the press columns as in my former patent I prefer to arrange a plurality of boxes arranged one above the other in any number found desirable, such boxes being virtually identical in construction and adapted to be held together so as to form one long box pivoted on each pillar. Each box is composed of a fixed side and end and also of a hinged side and end.

To the fixed side is secured brackets *n*¹ secured to or forming part of sleeves *o* mounted on the press columns, ball bearings being provided to minimize friction. The hinged sides and ends *n*² and *n*³ are secured together by catch levers *p* pivoted at *p*¹ the outer end of such levers engaging with pins *p*² or projecting studs on the hinged sides. The rear ends of the catch levers are coupled together by a rod *q* so that the movement of one lever transmits motion to the other and so releases the catches simultaneously. The separate boxes are held together by projections *r* at their rear which overlap the top and bottom ends, respectively, of the superposed boxes limiting movement in one direction. The boxes are held in line with such projections by pivoted tumbler catches *r*¹ secured to the two bottom boxes as shown in Fig. 1, such catches having inclined ends so that as each superposed box is pushed towards the lower one the catches are auto-

matically depressed but afterwards rise into position and lock the parts together. The press boxes so locked are brought into position in the center of the press, after being filled with the material to be pressed.

Each bottom box is provided with a sliding bottom *s* as indicated more clearly in Fig. 4. This is preferably tapered and its ends are supported in slideways in the box. The bottom is placed in position prior to the box being filled with the material to be pressed and remains in this position until the box is brought over the press follower as already stated. Prior to the follower being raised the bottom is slid out of position. For this purpose one or a pair of hand levers *s*² is provided pivoted to the body of the box near the bottom. To this hand lever is centrally pivoted a second lever *s*¹, the lower end of which is coupled to the rear end of the box bottom while its upper end is provided with a pin adapted to slide in the slot of a slotted bracket *s*³ so that as the hand lever is pulled forward the lever secured to the box bottom can pass out with the latter at the foot while its upper end descends in the slot of the brackets. Two pairs of the levers are preferably employed arranged in or about the positions indicated in Fig. 4.

The press follower *e* is made sufficiently deep to be longer than each section of the combined box so that in rising to compress the material it may push the latter through one box and enter itself into the other prior to the latter being automatically turned out of the way as will be hereinafter described. Further, the follower being, as already stated, deeper than any section of the box the joints *e*¹ never enter the box consequently they can be made any size. For instance, if the box is four feet by sixteen inches the size over the joints *e*¹ can be five feet by two feet, if necessary, to get a suitable joint, a construction not possible in any other toggle press. The part *e* of the follower that travels into the box must of necessity be smaller than the box, and this has prevented the toggle lever presses being used for making the Indian size bales owing to there being not sufficient room in the box for the working parts. In the present press the working parts do not go into the box. To guide the follower for the early part of its lift I provide in its sides grooves *t* or secure to its sides strips to form a groove and to the base of the press I secure upstanding brackets *t*², the upper ends of which support anti-friction bowls *t*³ to engage with the grooves in the follower. The latter is thereby kept in a truly horizontal position while passing through the first box. The bowls also act as a stop to limit the downward movement of the follower after pressing.

In order to automatically disengage the catch levers *p* and to turn each box away

from the press as the follower rises through each of them I connect the rear end of the bottom lever p in each box to the rear end of a lever u pivoted at u^1 to a bracket supported 5 from the sleeve o the other end of such lever being coupled to a pin u^2 passing through a vertical hole in the sleeve and projecting a little beyond it. And, on the follower of the press I secure brackets v supporting a shaft 10 or studs on which is mounted rollers or bowls v^1 . As the press follower rises one of these rollers comes into contact with the pin u^2 thereby lifting it and in turn causing the lever u to operate the bottom catch lever p and 15 through the connecting rod q the upper catch lever p as well thereby disengaging the catches and allowing the hinged side and end to open. Immediately after this action the roller v^1 comes into contact with a projecting 20 inclined plane v^2 forming part of the sleeve o and as a result the latter and with it the box is turned away from the press. It will be observed however that the press follower is of 25 such a length that prior to the two actions taking place its upper end has forced the material into the second box of the series and as it passes further upward into the third or following box the same actions occur until finally the whole of the material is forced into 30 the press chamber w which is pivoted to the upper end of the press columns and about which it can be turned as in my previous patent. The bale is held between the press head and follower while being lashed, but it is necessary to have the bale chamber doors open 35 to get the hoops round the bale. The latter is secured by a bale covering and bale ties or hoops or by the latter alone as will be well understood. The compressed bale can then 40 be removed after the press follower descends to compress the next lot of material in the second range of boxes which have meantime been filled.

The mechanism for operating the press 45 boxes in the manner described may, of course, be applied in connection with presses having only one box or one box on each of the four press columns.

What I claim as my invention and desire 50 to secure by Letters Patent is:—

1. A toggle lever baling press having a plurality of press boxes arranged one above the other, sleeves on the press column supporting the boxes, and pivoted tumbler catches 55 for holding the separated boxes together during the pressing operation.

2. In toggle lever presses of the type referred to press boxes each provided with a hinged side and end, projections on the 60 hinged side, a pair or more of pivoted catch levers on the end of the box adapted to engage with the projections, a rod coupling the

rear ends of the catch levers together, a second lever pivoted to the sleeve carrying the box engaging at one end with one of the pivoted catch levers and coupled at the other to a pin passing through a hole in the supporting sleeve and a roller carried by the press follower adapted to come in contact with the pin so as to operate it and the arrangement 65 of levers and so release the catches from the projections substantially as described.

3. In a toggle lever baling press, the combination with a plurality of press boxes, of means for supporting the boxes in the path 75 of travel of the press follower, means for moving each press box clear of the press follower consisting of a projecting inclined plane on each box support, means for releasing the boxes, and means on the press follower 80 acting on the inclined planes for moving the box support.

4. In a toggle lever press of the type referred to the means for controlling the opening and closing of the bottom press box consisting of a bottom of an inclined character arranged in sideways in the box, a lever pivoted by one end to the box bottom, slotted brackets with which the upper end of the lever engages and a lever pivoted to the box 90 and to the first-named lever for operating the parts substantially as described.

5. The combination in a baling press, a press column, a press follower, sleeves rotatable on the press column and having projecting inclined planes, means for connecting the press boxes to the sleeves to take motion therefrom, and means on the press follower adapted to actuate the box releasing mechanism and engage the inclined planes to rotate the sleeves.

6. In a toggle lever press, press columns, a follower, counter-balance levers and rods at the exterior of the press columns, levers for operating the follower and means for connecting the counter balance levers and rods 105 and means actuated by the follower for moving the counterbalance levers and rods.

7. In a toggle lever baling press, press boxes having upper and lower compartments, a follower adapted to enter an upper compartment of the press box prior to opening and releasing the lower compartment of said box, means for holding the compartments of the box in operative relation, and means for releasing said holding means and simultaneously rotating the released compartment.

In testimony whereof I have hereunto set my hand in the presence of two witnesses. 110

HUGH IORWERTH ROBERTS.
